UNITED STATES PATENT OFFICE.

ALLEN LOOMIS, OF TOLEDO, OHIO.

OCTAVE KEY.

Application filed February 9, 1923, Serial No. 617,952. Renewed March 19, 1926.

This invention is concerned with an octave key for musical instruments of the wood wind type and has been designed with special reference to the saxophone. Hence, in describing the particular embodiment of the invention illustrated in this specification, I will generally, when occasion arises to speak of the instrument by name, identify it as a saxophone. However, this mode of description is not intended to indicate, or be construed as, a limitation of the principles of the invention exclusively to any specific instrument; but, on the contrary, so far as my claim to protection is concerned, I claim and desire to protect all novel characteristics and principles of this invention in combination with its application to any musical instrument of the wood wind type with which it is capable of being used, whether in the precise form here shown and described or with modifications in form and arrangement. Within the meaning of the term "wood wind type" as used in the foregoing definition I include all musical instruments of which the characteristic is a tubular body which contains a vibrating column of air and which has lateral holes adapted to be opened and closed for determining the length of the vibrating air column and hence the pitch of the emitted note, whether actually made of wood or of metal or other material.

My present object has been to furnish an octave key mechanism which will combine the following qualities and characteristics:—

1. The minimum number of springs consistent with operation in the desired manner, and the elimination of certain springs which have been necessary in prior designs and are there frequently a cause of trouble and annoyance.

2. Certainty of action, and limitation of the employment of the operating keys to fixed paths of short extent; and particularly avoidance of liability of the key jumping when transition is made, in the course of playing, from certain notes in one register to certain notes in another register of the same instrument.

3. Ability of both octave hole stoppers to move directly toward and away from the holes which they respectively cover, without rubbing or scuffing across the rim of the hole at any time or under any conditions.

4. Generally an efficient mechanical design, conforming to good principles of engineering and one which is capable of being

produced in quantities with accuracy and uniformity between corresponding parts of duplicate lots.

In the drawings which accompany and form part of this specification—

Figure 1 is a perspective view showing the upper part of the body tube and the attached mouth tube of a saxophone having my improved octave key applied thereto.

Figure 2 is a diagrammatic or development view showing the octave key mechanism and supporting parts resolved into a single plane.

Figures 3 and 4 are cross sections taken approximately on lines 3—3 and 4—4, respectively, of Figure 1.

In these drawings the tone holes, tone-hole stoppers, and operating keys which are actually on the part of the instrument here represented, are omitted, with one exception at the top of Figure 3, and only those parts are shown which comprise, or are essential to the operation of, the octave key mechanism. 75

Like reference characters designate the same parts wherever they occur in all the figures.

The numeral 5 designates the body tube of a saxophone and 6 designates the curved mouth tube which is detachably applied to the upper end of the saxophone in a manner common to all instruments of this class. The mouthpiece or reed (not here shown) is adapted to be applied to the end 7 of the mouth tube. The upper octave hole 8 is 80 formed in the mouth tube and is covered by a pad or stopper 9 which is carried by a curved lever or key 10 supported by a pivot 11. The lever 10 carries a spring 12, one end of which is secured to the lever and the 85 other end of which presses against the tube with tendency to hold the stopper or pad 9 against the rim of the hole 8. The lever 10 extends to a point near the upper end of the body tube and carries a ring 13 which surrounds the adjacent part of the mouth tube and is adapted to be entered by the arm 14 of a lever presently described. Said ring 13 is an abutment for the key 10 by and

through which forces and reactions are transmitted between said key and the lever arm 14. The spring 12 impels this controlling abutment toward the reacting surface of arm 14, as well as moving the stopper 4 90 toward the octave hole 8. 95

The lower octave hole is formed in the body tube and is covered by a pad or stopper

- 15 carried by an angular or bent arm 16 which projects from and is secured to a sleeve 17 confined between posts 18 and 19 and having a rotative bearing on a rod 20. 33. Thus a sliding and pivotal connection is provided between the floating lever and the lower octave hole key which is capable of transmitting force in either direction, and the slotted arm 33 of the floating lever is one of the parts or elements of such connection. The provision of such connection enables the lower octave key to be made springless; that is, without any immediate and constantly acting spring tending to hold it either in its depressed or its raised position. On the opposite side of the same arm is a lug or ledge 39 (constructed preferably as a rectangle brazed along two edges to the arm 16 in the angle thereof) arranged under the projecting end of an arm 40 which is pivoted on the pivot rod 20. Arm 40 has an extension 41 at the opposite side of the pivot rod, and this extension is connected, by means of a bridge rod 42, with an arm 43, secured to a sleeve 44 and pivoted upon rod 20. Arm 43 carries a finger key 45 and is also connected to mechanism for operating a tone hole stopper or cover, although the latter mechanism and stopper are not shown in these drawings. 70 75 80 85 90 95 100 105 110 115 120 125
- 5 Arms and equivalent structures for like purposes to the arm 16 (and likewise the lever 10) are usually called "keys" or "octave keys" in the art, and may therefore be so called in this specification. Said rod 20 extends through a considerable proportion of the length of the body tube, being supported by pillars, as clearly shown in the drawings, and serves as a pivot support for many of the key mechanisms. It provides a fixed axis for the stopper 15 near the plane of the rim of the octave hole, enabling the stopper to open and close without, in any circumstances, sliding or scuffing across such rim. Preferably the distance of said axis from the plane just identified is not more than half the distance of the axis from the nearer edge of the rim.
- 10 Another rod 21 having a similar office and arrangement to the rod 20 is supported by posts 22, 23 and others, and serves as the pivot about which a sleeve 24 turns. Secured to this sleeve are two arms 25 and 26, a finger key 27, and a hook or spring abutment 28. Said arms carry a tube or sleeve 29 which serves as the support or bearing for a rod 30 (shown dotted in Figure 2 and in section in Figure 3).
- 15 A bar 31 lies beside the sleeve 29 and its upper end is offset so as to furnish a cross-piece 32 and the arm 14 previously mentioned. The cross-piece 32 lies across the end of sleeve 29 and receives one end of the pivot rod 30. The lower end 33 of the bar 31 is bent to the opposite side away from the sleeve 29 and is formed with a notch 34 (Figure 4), being thus a notched or forked arm. A lug 35 is also provided on this part of the bar and extends oppositely to the arm 33 and across the lower end of sleeve 29, receiving the adjacent end of the pivot rod 30. Thus the bar 31 forms a lever having two arms, namely, 14 and 33, which extend to opposite sides, respectively, of the pivot rod 30. Moreover, since the pivot rod is movable about the axis of the sleeve 24, so that the whole lever is movable bodily, or, in other words, is mounted in a floating manner, I call the lever a "floating lever." The sleeves 24, 29, arms 25, 26, and pivot rod 30 form the carrier of the floating lever.
- 20 A spring 36 projects from the post or pillar 23 and bears against the hook or abutment 28, tending constantly to swing the sleeve 29 toward the body of the instrument; in other words, to depress the pivot of the floating lever, and at the same time raise the key 27.
- 25 The bent arm 16 of the octave hole stopper 15 carries a pin 37 on which is a block 38 which fits slidingly in the notch 34 of arm
33. Thus a sliding and pivotal connection is provided between the floating lever and the lower octave hole key which is capable of transmitting force in either direction, and the slotted arm 33 of the floating lever is one of the parts or elements of such connection. The provision of such connection enables the lower octave key to be made springless; that is, without any immediate and constantly acting spring tending to hold it either in its depressed or its raised position. On the opposite side of the same arm is a lug or ledge 39 (constructed preferably as a rectangle brazed along two edges to the arm 16 in the angle thereof) arranged under the projecting end of an arm 40 which is pivoted on the pivot rod 20. Arm 40 has an extension 41 at the opposite side of the pivot rod, and this extension is connected, by means of a bridge rod 42, with an arm 43, secured to a sleeve 44 and pivoted upon rod 20. Arm 43 carries a finger key 45 and is also connected to mechanism for operating a tone hole stopper or cover, although the latter mechanism and stopper are not shown in these drawings. 70 75 80 85 90 95 100 105 110 115 120 125
- In the saxophone for which the herein illustrated mechanism is designed, the hole stopper controlled by the key 45 is normally opened by its spring, and the spring acting for that purpose also tends to raise finger key 45 and to depress arm 40, and the octave hole stopper 15. In addition, and supplementing that tendency, I have provided a needle spring 46 which is anchored in a pillar 47 and bears on a spring abutment hook 48 projecting from sleeve 44. For the purposes of the octave key mechanism alone, the spring 46 is the only spring necessary to raise key 45 and depress key stopper 15, but it may be considered as typifying any spring applied for that purpose, whether it is arranged as shown or is an otherwise arranged spring acting to open the tone hole cover controlled by the key 45. 100 105 110 115 120 125
- It will now be seen that the tendency of the springs 12, 36 and 46, and their effect when neither key 27 or 45 is pressed upon, is to close both octave hole stoppers 9 and 15. Now, if the key 27 is pressed upon, the pivot 30 of the floating lever 14, 31, 33 is raised. Thus the effect on the floating lever of the spring 46, acting through the short arm 40 and the longer arm 33, 35 of the floating lever, is greater than the effect of the spring 12 acting through a much longer arm of lever 10 and a shorter arm of the floating lever. Hence, when the pivot of the floating lever is raised by depressing keys 27, as just described, the pin 37 remains in the same position and the whole floating lever is swung about this pin as a fulcrum, raising its arm 14, and so raising the stopper of the upper octave hole. If, while pressure is maintained on key 27, the key 45 is pressed

upon, then the force exerted by spring 46 is overcome and the restraint previously exerted on the stopper arm 16 and pin 37 is removed and the spring 12 is unopposed. 5 The latter spring, therefore, is permitted to close the upper octave hole stopper 9, and open the lower octave hole stopper 15, transmitting motion thereto through the floating lever, which then turns freely about its own 10 pivot 30. Then, if the key 27 is released while pressure is maintained on key 45, the stopper 15 is closed without causing stopper 9 to be opened, through the movement of the floating lever bodily toward the instrument 15 body.

If finger key 45 alone is depressed, both octave hole stoppers remain closed, the stopper 9 being so held by its spring 12, and the stopper 15 by the combined action 20 of the spring 36 and the reaction of the instrument body on the floating lever and its carrier. The upward force of reaction of the body on the floating lever arm 14, and the downward force of the carrier on 25 the floating lever pivot 30, due to the spring 36, produce the downward force on pin 37 which is necessary and sufficient to hold the lower octave key in closed position. However, if finger key 27 is depressed during 30 the operation of finger key 45, the lower octave hole is opened, while the upper octave hole remains closed, for at this time the ring 13 holds the floating lever arm 14 down, due to the force of spring 12, and said ring 35 then serves as an abutment for the floating lever while the pivot of the latter is moved away from the body.

The particular saxophone here illustrated is the C melody instrument, and the key 45 40 controls the A natural tone hole, being depressed when all notes below A are played and released when A or any note above it is played. In passing from the lower register into the lower part of the middle register, the stopper 15 must be opened and the stopper 9 must be closed. This transition occurs at a pitch below A, and the opening of the stopper 15 is effected by pressing key 27 while key 45 is held down. When 45 A or any higher note is played in the second register the stopper 15 must be closed and the stopper 9 opened; that is, a reversal of the condition just above described must take place. The mechanism automatically 50 accomplishes this reversal of the stoppers because the performer, when playing A or any higher note, releases the key 45, and the spring-actuated rise of this key, with descent of arm 40, then closes stopper 15, and, by turning the floating lever about its own pivot 30 as a fulcrum, opens the stopper 9. 55 When it becomes necessary to close the tone hole stopper controlled by the key 45, and at the same time to open the octave 60 hole stopper 15, as is the case when passing from the upper part of the lower register to the lower part of the upper register, the keys 45 and 27 may be pressed upon nearly simultaneously, but with the key 45 70 a little in advance of the other, or the key 45 may be pressed upon any length of time in advance of the key 27, and then when key 27 is depressed stopper 15 will be opened without causing stopper 9 to "jump." In 75 this respect my mechanism has a great advantage over the octave keys previously used on saxophones because, in the circumstances just described, the opening of the lower octave hole in making this transition always 80 causes the upper octave hole stopper to "jump." The prevention of "jumping" is one of the objects and accomplishments of the invention.

For the rest it will be seen that a minimum of three springs is sufficient for all the required movements and actions of the octave key mechanism; and when the finger key 45 is already adequately controlled by the spring of a tone hole mechanism, only 85 two additional springs are required for complete control of the octave key mechanism. The lower octave key, being itself springless, is subject to being closed by either the spring which controls the finger key 45 or by force originating from the spring which controls the finger key 27; while it opposes no resistance to being opened by the forces applied from the finger key 27 and the comparatively weak closing spring of the upper 90 octave hole key. For the rest, the mechanism is simple, and one which can be accurately made and readily assembled.

In this specification the terms "depress", "down" and similar terms, have the meaning of movement or direction toward, or position near, the body of the instrument; while the terms "raise", "upward", and terms of similar import have the contrary meaning. That is, a stopper or key or other part is considered to be depressed when it is moved toward or lies near the instrument body, whatever may be the actual direction in which it is moved in reaching such position, while it is considered to be 105 raised when moved or held away from the body; and the same meaning is understood with reference to the directions in which the force of the springs and the performer's 110 digits act on the keys and stopper.

What I claim and desire to secure by Letters Patent is:

1. The combination, in a musical instrument of the wood wind type having two octave hole stoppers, of a floating lever carrier movably supported from the body of the instrument, a floating lever movably mounted on said carrier and having articulated connection with both stoppers, a finger key controlling a tone hole cover 125

- of the instrument and spring-impelled to its normal position, an arm connected to said finger key and bearing on one of the octave hole stoppers to hold the same closed when said key is in the normal position, but arranged to release said octave hole stopper when the key is pressed upon, a second key connected with the pivot of said floating lever, a spring acting on said second key for normally raising the same, and a spring acting on the other octave hole stopper with tendency to close it.
2. In a musical instrument of the wood wind type, an octave key mechanism comprising two octave hole stoppers, each pivoted to turn about a fixed axis and having their only motion about said axes, a floating lever carrier pivotally supported from the body of the instrument to turn about an axis approximately parallel to the axis of one of said stoppers, a floating lever pivoted to said carrier to turn about an axis approximately parallel to the axis of the latter and being articulated to both said stoppers, and a tone hole key mechanism having means for exerting pressure on one of said stoppers tending to close it.
3. In a musical instrument of the wood wind type, a body having two octave holes, stoppers for said holes, both pivotally supported from the instrument body and being movable only about their respective pivots, the pivot of one of said stoppers being approximately parallel to the instrument body, a floating lever articulated to both stoppers, a floating lever carrier pivotally mounted on the instrument body and to which the floating lever is pivoted on a different axis, and yielding means tending constantly to depress both stoppers and the pivot of said floating lever, and a finger key for relaxing the pressure of the yielding means on one of said stoppers.
4. An octave key mechanism for musical instruments of the wood wind type having a body tube and a separate mouth tube and having octave holes on the body and mouth tubes, respectively, an octave hole stopper and a carrying lever therefor pivoted on the mouth tube, said lever extending longitudinally of the mouth tube and having a ring adapted to surround the body tube, a floating lever carrier pivotally mounted on the body tube to swing about an axis extending longitudinally thereof, a floating lever pivoted to said carrier on a parallel axis, said floating lever having an arm offset from its pivot extending along the body tube and adapted to enter said ring, said floating lever also having another arm extending cross wise of the body tube, a second stopper pivotally mounted on the body tube to swing about a longitudinal axis and in position to cover the second octave hole, a sliding and pivotal connection between said second stopper and the second arm of the floating lever, and a key engaged with said second stopper.
5. In an octave key mechanism of the class described, a floating lever carrier having a pivot, and a floating lever consisting of a bar having alined pivot bearings, engaged in said pivot; said floating lever being offset at opposite ends and in opposite directions from the line of said pivot bearings.
6. In an octave key mechanism of the class described, a floating lever consisting of a bar having alined pivot bearings, and being offset at opposite ends and in opposite directions from the line of said pivot bearings, and a floating lever carrier having a pivot engaged with said bearings, one end of said lever being formed as one part of a sliding and pivotal connection capable of transmitting force in both directions, and its other end being formed with a longitudinally extending arm.
7. In an octave key mechanism of the class described the combination, with two octave keys, of a floating lever carrier pivoted to the body of the instrument, a floating lever pivoted to said carrier and having an arm formed with two surfaces engaged with one of said octave keys to transmit force to the latter in respectively opposite directions, said lever having a second arm arranged to react on the instrument body when so exerting force in one direction, and the other octave key being engaged with said second arm to receive force applied in one direction by the latter and having a spring arranged to cause force application through said last-named octave key in the opposite direction against said arm.
8. In a musical instrument of the wood wind type, an octave key mechanism comprising two octave hole stoppers, both pivoted directly to the instrument body, a floating lever articulated to both stoppers, a pivotally mounted carrier to which said floating lever is pivoted on an axis beside the axis of the carrier, springs acting on said floating lever carrier and on one of the octave hole stoppers in directions tending to hold both stoppers closed, and a spring-impelled tone hole key mechanism having means for exerting pressure in the closing direction on the other of said octave hole stoppers, but adapted to release said pressure when pressed upon.
9. In a musical instrument of the wood wind type having upper and lower octave holes, a stopper key for each of said octave holes, both said keys being pivoted to the instrument body, a spring pressed finger key having a member arranged to bear on the lower octave hole stopper key, a floating lever carrier pivoted to the instrument body and having a finger key and a spring for

moving it, a floating lever pivoted to said carrier having an arm connected with the stopper key for the lower octave hole and a contact surface, and a spring exerting force 5 on said upper octave hole key tending to move its stopper toward the upper octave hole, said key having an abutment arranged to be impelled by the last named spring at the same time toward said contact surface 10 of the floating lever.

10. In a saxophone the combination, with a body tube, of a detachable mouth tube pierced with an octave hole, a movable spring-actuated octave key including a stopper 15 for said hole and an extension serving as an operating abutment, said body tube being pierced with a second octave hole, a spring-actuated and pivotally mounted finger key adapted to operate a tone hole stopper 20 of the instrument, a springless octave key for said second octave hole pivotally mounted on said body tube and arranged to close said second octave hole, operating connections through which the said finger key 25 is adapted to close said springless octave key when not depressed by the performer's finger, a second spring-actuated finger key pivotally mounted on said body tube, a floating lever carrier connected with said second 30 finger key to be moved by movement of the latter, and a floating lever pivotally mounted on said bearing and having parts arranged to raise the first-named octave key and to raise or depress the second-named octave key 35 when the latter is free from control by the first-named finger key.

11. In a saxophone the combination, with a body tube, of a detachable mouth tube pierced with an octave hole, a movable spring-actuated octave key including a stopper 40 for said hole and an extension serving as an operating abutment, said body tube being pierced with a second octave hole, a spring-actuated and pivotally mounted finger key adapted to operate a tone hole stopper of the instrument, a springless second octave key pivotally mounted on said body tube, arranged to close said second octave hole and being coaxial with said finger key, 45 operating connections through which the said finger key is adapted to close said second octave key when not depressed by the performer's finger, a second spring-actuated finger key pivotally mounted on said body 50 tube, a floating lever bearing connected to and movable by said second finger key, and a floating lever pivotally mounted on said bearing and having parts arranged to raise the upper octave key and to raise or depress the lower octave key when the latter is free 55 from control by the first-named finger key.

12. In a saxophone the combination, with a body tube, of a detachable mouth tube pierced with an octave hole, a movable spring- 60 actuated octave key including a stopper for

said hole and an extension serving as an operating connection, said body tube being pierced with a lower octave hole, a spring-actuated and pivotally mounted finger key adapted to operate a tone hole stopper of 70 the instrument, a springless lower octave key pivotally mounted on said body tube and arranged to close said lower octave hole, operating connections through which the said finger key is adapted to close said lower 75 octave key when not depressed by the performer's finger, a second spring-actuated finger key pivotally mounted on said body tube, a floating lever bearing approximately parallel to said body connected to and movable by said second finger key, and a floating lever pivotally mounted on said bearing and having parts arranged to raise the upper octave key and to raise or depress the lower octave key when the latter is free 80 from control by the first-named finger key.

13. In a musical instrument of the wood wind type, a body having octave holes, a springless stopper key for one of said holes, a spring closed stopper key for one of said holes, a finger operable key, a spring acting on said last named key in opposition to the pressure applied thereto by the performer's finger, means for applying the force of the 90 said spring to the springless octave key in the direction for closing the latter when the finger key is free of finger pressure, a second finger key pivoted to the instrument, a floating lever fulcrum carried by said second finger key at the opposite side of the pivot thereof from the finger actuated part of this key, a spring acting on said second finger key with tendency to depress said fulcrum, a floating lever pivoted on said fulcrum and having two arms, one of which is connected to the springless stopper key with ability to apply force thereto for both closing and opening it and the other arm is arranged to react on the body and to rise 100 from the body, and an abutment for said other arm actuated by the spring of said spring closed stopper key to apply pressure on such arm toward the body, and arranged to open the spring closed stopper key when 110 said arm is raised.

14. In a musical instrument of the wood wind type, a body having two octave holes, stoppers for said holes, both pivotally supported from the instrument body and being 120 movable only about their respective pivots, the pivot of one of said stoppers being approximately parallel to the instrument body, a floating lever carrier having a finger key pivotally supported from the instrument body on an axis approximately parallel thereto, a floating lever pivoted to said carrier on a different axis, also approximately parallel to the body, motion 125 transmitting connections between said float- 130

ing lever and both of said stoppers, separate springs tending to depress both stoppers and the pivot of the floating lever, and a key operable to relax the spring pressure on one of said stoppers.

15. In an octave key mechanism of the class described, an octave key pivotally supported from the body of the instrument, a floating lever carrier pivotally supported from the body of the instrument, a floating lever pivoted to said carrier on a different axis from that of the carrier, said lever having an arm with a guideway, a block mounted to slide in said guideway and having pivotal connection with said stopper, the floating lever having a second arm adapted to react on the instrument body, and a spring actuated second octave key in connection with the second named arm for transmission of pressure to and from the same.

16. In an octave key mechanism of the class described, the combination with an octave hole stopper of a floating lever carrier pivotally connected to the instrument body, a floating lever pivoted to said carrier on a different axis from that of the carrier and having a slotted arm, and a block mounted to slide in said slotted arm and having a pivotal connection with the stopper key.

17. In a musical instrument of the wood wind type, a key mechanism including a member pivotally supported from the body of the instrument, a second member pivotally mounted in a floating manner, a carrier on which said floating member is pivoted and being in turn pivotally supported from the instrument body, one of said members having a slot, and a block mounted to move slidably in said slot and pivoted to the other of said members.

18. In an octave key mechanism of the class described, a floating lever, a carrier pivotally supported from the instrument body and to which said floating lever is pivoted on an axis approximately parallel to the body, and a stopper key pivotally supported from the body, said stopper key and one arm of the floating lever having sliding and pivotal connection capable of transmitting force in either direction of their permitted movements.

19. In a musical instrument of the wood wind type, the combination of a key and an operating lever, one of the before named members having an arm with an open notch and guiding surfaces bounding such notch, a block slidably engaged with said bounding surfaces and adapted to enter the open end of the notch, and a pivot carried by the

other of said members and contained in said block.

20. In a musical instrument of the wood wind type, a pivotally mounted stopper key having a projecting pivot, a slide block mounted on said pivot with provision for rotary movement thereon, and an operating arm for said key having an open notch to receive said block and having guiding and bounding surfaces on which said block is adapted to slide when the parts are in operative assembled relation.

21. In a musical instrument of the wood wind type, an octave key, a block pivotally connected to said octave key, a floating lever having an arm with an open notch adapted to receive and engage said block, and a floating lever carrier pivoted to the instrument body and to which the floating lever is pivoted.

22. In a musical instrument of the wood wind type, an octave key, a block pivotally connected to said octave key, a floating lever having an arm with an open notch adapted to receive and engage said block, and a floating lever carrier pivoted to the instrument body and to which the floating lever is pivoted, the pivot for said floating lever extending longitudinally of the instrument, and the floating lever having longitudinally extended and aligned pivot bearings and having a second arm offset both longitudinally and laterally from the before named slotted arm.

23. In a musical instrument of the character set forth having two octave holes, separate keys for said octave holes pivotally supported from the body of the instrument, a floating lever carrier also pivotally supported from said body, a floating lever pivoted to said carrier on a different axis from that of the carrier, said keys, carrier and floating lever all being arranged to turn about axes substantially parallel to the instrument body, a connection between one arm of said floating lever and one of the octave keys, the other arm of said floating lever being arranged to bear on the instrument body when the pivot of said floating lever is depressed, a spring acting on said carrier tending to depress said pivot, the last named arm of the floating lever then reacting on the body and exerting closing pressure on the said octave key, and a connection between the other key and the last named arm of the floating lever for raising said key when said arm is raised.

In testimony whereof I have affixed my signature.

ALLEN LOOMIS,
